UNITED STATES PATENT OFFICE

2,457,364

DESK TRAY

Maxfield Gluckman, Jackson Heights, N. Y.

Application August 28, 1944, Serial No. 551,506

4 Claims. (Cl. 129—35)

1

This invention relates to new and useful improvements in desk trays such as are used for holding papers in a confined and orderly manner. Conventional desk trays serve their useful purpose, but under certain conditions it is necessary to use weights to hold papers in place, especially if there is a wind or air currents from electric fans.

Therefore, the principal object of the present invention is to provide a desk tray improved to the extent of being equipped with paper retaining means.

Another object of the invention is to provide a desk tray capable of being moved to a position to receive papers, and which upon being released will act to grip the contained papers to prevent the same from being blown or accidentally displaced from the tray.

Various other important objects and advantages of the invention shall become apparent from the drawings and the following description.

In the drawings:

Figure 1 is a side elevation of the walled type of tray.

Figure 2 is a top plane view of the structure shown in Figure 1.

Figure 3 is a vertical section taken on line 3—3 of Figure 2.

Figure 4 is a cross section taken on line 4—4 of Figure 3.

Figure 5 is a vertical longitudinal section showing how papers can be retained in folded back position.

Figure 6 is a top plan view of a modified open type tray.

Figure 7 is a vertical section taken on line 7—7 of Figure 6.

Figure 8 is a vertical section similar to that of Figure 7, but modified to show desk attaching means.

Figure 9 is a fragmentary detailed sectional view showing modified spring pressure means.

Figure 10 is a fragmentary vertical sectional view showing another form of pressure exerting means.

Figure 11 is a further modification of the device.

Referring to the drawings wherein like numerals designate like parts, numeral 5 denotes a tray having side walls 6—6 and an interrupted front wall 7. The break in the front wall facilitates reaching for, and lifting of papers from the tray, and also permits freedom of access to the tray when folding papers back to a retained position as shown in Figure 5.

2

Secured to the under side of the tray 5 are bearings 8 which receive trunnions 9 at the ends of a base bar 10 which function as a fulcrum point. The bar 10 is notched at its intermediate portion to interlock with a right angularly disposed base bar 11. Both of the bars 10 and 11 are provided with felt supporting pads 12. In the present instance, the bearings are shown as inwardly extended notches across which a plate is secured for retaining the trunnions.

The rear end of the base bar 11 has a tongue 13 which fits into a recess in a clamp block 14, the latter also being provided with a felt support pad 15.

The upper end of the block 14 has a forwardly projecting abutment 16 overlying the rear edge portion of the tray 5.

At this point it should be noted that the fulcrum point for the tray 5 (bearings 8 and trunnions 9) is toward the rear edge of the tray, resulting in the forward edge gravitating or overbalancing to result in the rear edge portion coming into contact with the abutment 16. If any papers are in the trays, these will be held between the tray 5 and the abutment 16. Papers in the tray can be folded back and held in this position by being disposed under the abutment 16, to the end that papers underneath may be read without using a hand to hold the overlying papers.

Figures 6 and 7 show a modification. This form of the invention depicts a tray 5—a without any side walls, the tray 5—a being supported by bearings 8—a receiving trunnions 9—a, the latter being located on the ends of a base bar 10—a interlocked with a base bar 11—a. The bar 11—a has a tongue and recess connection with a block 14—a formed with an abutment 16—a wedging the rear edge of the tray 5—a.

Secured to the rear end portion of the base bar 11—a is an upstanding strip spring 17 bearing against the underside of the rear edge portion of the tray 5—a. This exerts pressure in the tray 5—a for more firmly clamping papers against the abutment 16—a, this being especially desirable with this type of tray because of the lack of walls.

In Figure 8 a further form of the device is shown, in which the abutment 16—b is in the form of a plate secured to the block 14—b in any approved manner. The plate projects beyond the block and is provided with spaced apertures 18—b cooperable with upstanding pins 18—c. Preferably the paper sheets 18—d will be provided with perforations adapted to register with the pins 18—c. This type of holder is

intended for mounting a wall or similar surface and to accomplish this, the block is formed with an apertured ear 18 through which a screw 19 is extended for engaging a wall surface.

The fragmentary view Figure 9 shows a tray 5-c, a base bar 11-c, a block 14-c on the block 14-c overlying the tray 5-c. The difference in this form of the invention over the other is the presence of a coiled compression spring 20 interposed between the base bar 11-c and the tray 5-c and acting in the same capacity as the spring 17 in Figure 7.

A further modification is shown in Figure 10. Here the tray is denoted by reference character 5-d, a base bar by 11-d, a block by 14-d and an abutment on the block by 16-d.

The difference between the form of the invention shown in Figure 10 and those shown in Figures 7 and 9 is the provision of a block of flexible rubber, such as sponge rubber interposed between the base bar 11-d and the abutment 16-d in place of a strip spring 17 or a coiled spring 20.

A cushioning strip 21 may be employed on the under face of the abutments as shown in Figures 9 and 10.

As shown in Figure 11, the clamp block 14 may be formed integrally with the fulcrum 10.

Obviously, a tray constructed as above explained obviates the necessity of employing paper weights to hold papers in desk trays, and in addition offers an effective means for holding papers folded back in the tray, in order that typists may copy underlying papers conveniently.

It will be apparent that paper sheets may be inserted while the bottom of the hand presses the tray downwardly at the same time.

I claim:

1. A desk tray comprising a base having an abutment overlying one end thereof, a fulcrum on the base positioned substantially intermediate of the base, a tray device rockably supported on said fulcrum and having a projected portion beneath said abutment, the end of the tray opposite the abutment being of a weight to move the projected portion of the tray into contacting engagement with the abutment.

2. A desk tray comprising a base having an abutment overlying one end, a pivot means on

the base, a tray device rockably supported on said pivot means, said tray being heavier at the end opposite the abutment, and said tray having a portion disposed beneath said abutment and normally held thereagainst.

3. A desk tray comprising a base consisting of a pair of crossed members, one crossed member projecting above the other to form a fulcrum, a block secured to one end of the other crossed member, an abutment on the block overlying the base, an article support rockably mounted on the fulcrum, and having one end disposed beneath the abutment, the opposite end of the support being heavier to hold the first named end of the support against said abutment.

4. A desk tray comprising a base consisting of a pair of crossed members, one crossed member projecting above the other and having a trunnion at the ends thereof, an article support having respective bearings for reception of said trunnions for rockably supporting said article support, an upright block on the other of said crossed members having an abutment overlying an end of said article support, the end of the article support opposite the abutment being heavier to hold the first named end of the article support in engagement with the abutment, but movable therefrom upon rocking movement of the article support.

MAXFIELD GLUCKMAN.
